ABSTRACT

An outdoor shelter having a tarp, a first loop at a first corner of the tarp on a first edge of the tarp, a second loop at a second corner of the tarp on the first edge of the tarp, a first rope at a first corner of the tarp on a second edge of the tarp opposite and parallel to the first edge of the tarp, and a second rope at a second corner of the tarp on the second edge of the tarp. The tarp, the first loop, the second loop, the first rope, and the second rope are stored in a pouch fixed to the tarp when the shelter is not in use. When needed, this outdoor shelter can be deployed in the shape of a lean-to or in the shape of a pointed snow plow.

OUTDOOR SHELTER AND METHODS OF DEPLOYING THE OUTDOOR SHELTER**CROSS-REFERENCE TO RELATED APPLICATION**

This application is a continuation of and claims benefit to U.S. patent application Ser. No. 16/859,474, filed on Apr. 27, 2020.

FIELD OF THE INVENTION

The present invention relates, in general, to shelters for individuals recreating outdoor and, in particular, to an outdoor shelter that provides protection for outdoor enthusiasts from inclement weather and methods for deploying this outdoor shelter.

BACKGROUND

One very important requirement for outdoor enthusiasts is that they know how to protect themselves from foul weather and have the means for protecting themselves from foul weather. This involves having a shelter that will protect them from foul weather that is easy to deploy in relatively quick time.

SUMMARY

An outdoor shelter, constructed in accordance with the present invention, includes a tarp, a first loop at a first corner of the tarp on a first edge of the tarp, a second loop at a second corner of the tarp on the first edge of the tarp, a first rope a first corner of the tarp on a second edge of the tarp opposite and parallel to the first edge of the tarp, and a second rope at a second corner of the tarp on the second edge of the tarp. This outdoor shelter also has a pouch fixed to the tarp and sized to contain the tarp, the first loop, the second loop, the first rope, and the second rope.

An outdoor shelter, constructed in accordance with the present invention, can be deployed in the shape of a lean-to and in the shape of a pointed snow plow. First, the tarp, the first loop fixed to the tarp, the second loop fixed to the tarp, the first rope fixed to the tarp, and the second rope fixed to the tarp are removed from the pouch. Next, a free end of the first rope is pulled around a first support structure and is tied to a selected location on the first rope. Next, a free end of the second rope is pulled around a second support structure and is tied to a selected location on the second rope. Next, the first loop and the second are secured to a base surface.

BRIEF DESCRIPTION OF THE DRAWINGS

FIG. 1 is a top view of a pouch containing the other parts of an outdoor shelter constructed in accordance with the present invention, namely a tarp, loops, and ropes.

FIG. 2 is a top view of the contents of the pouch shown in FIG. 1, namely a tarp, loops, and ropes.

FIG. 3 is a side view of an outdoor shelter constructed in accordance with the present invention deployed in the shape of a pointed snow plow.

FIG. 4 is a top view of an outdoor shelter constructed in accordance with the present invention deployed in the shape of a pointed snow plow.

FIG. 5 is a rear view an outdoor shelter constructed in accordance with the present invention deployed in the shape of a lean-to.

2

FIG. 6 is a side view of an outdoor shelter constructed in accordance with the present invention deployed in the shape of a lean-to.

FIG. 7 is a top view, on an enlarged scale, of a corner of the tarp having a loop.

FIG. 8 is a top view, on an enlarged scale, of a corner of the tarp having two ropes.

DETAILED DESCRIPTION OF THE INVENTION

Referring to FIGS. 1, 2, 7, and 8, an outdoor shelter, constructed in accordance with the present invention, includes a tarp 10. Tarp 10 is made of a waterproof, flexible, tear-resistant material, such as Xenon. However, one skilled in the art should appreciate that other material could be used. Tarp 10 has a size and a shape that, when deployed, it has the shape of a lean-to as illustrated in FIGS. 5 and 6 or as a pointed snow plow as illustrated in FIGS. 3 and 4. For the embodiment of the present invention illustrated and being described, tarp 10 is rectangular.

An outdoor shelter, constructed in accordance with the present invention, also includes a first loop 12 at a first corner 14 of tarp 10 on a first edge 16 of the tarp and a second loop 18 at a second corner 20 of the tarp on the first edge of the tarp. For the embodiment of the present invention illustrated and being described, loops 12 and 18 are ribbon loops that have sufficient width to fulfill a function that will be described below.

An outdoor shelter, constructed in accordance with the present invention, further includes a first rope 22 at a first corner 24 of tarp 10 on a second edge 26 of the tarp opposite and parallel to first edge 16 of the tarp and a second rope 28 at a second corner 30 of the tarp on the second edge of the tarp. For the embodiment of the present invention illustrated and being described, the outdoor shelter has a third rope 32 at first corner 24 of tarp 10 on second edge 26 of the tarp and a fourth rope 34 at second corner 30 of the tarp on the second edge of the tarp.

An outdoor shelter, constructed in accordance with the present invention, further includes a pouch 36 fixed to tarp 10 and sized to contain the tarp, first loop 12, second loop 18, first rope 22, second rope 28, third rope 32, and fourth rope 34. For the embodiment of the invention illustrated and being described, pouch 36 is fixed to tarp 10 at a corner of the tarp, namely corner 24.

Tarp 10 can be deployed in the shape of a lean-to, as illustrated in FIGS. 5 and 6, and in the shape of a pointed snow plow, as illustrated in FIGS. 3 and 4.

Deploying the Lean-To—FIGS. 5 and 6

Initially, tarp 10, first loop 12, second loop 18, first rope 22, second rope 28, third rope 32, and fourth rope 34 are removed from pouch 36.

A free end 22a of rope 22 is pulled around a first support structure, such as a tree 38, and is tied either to a selected location of rope 22 or to the free end of rope 32 which also has been pulled around tree 38.

A free end 28a of rope 28 is pulled around a second support structure, such as a tree 40, and is tied either to a selected location of rope 28 or to the free end of rope 34 which also has been pulled around tree 40.

First loop 12 is staked to a base surface, such as the ground 44, by a first elongated member, as seen in FIG. 3.

Second loop **18** is staked to the base surface **44** by a second elongated member, as seen in FIG. 3.

Deploying the Pointed Snow Plow Shape—FIGS. 3 and 4

Initially, tarp **10**, first loop **12**, second loop **18**, first rope **22**, second rope **28**, third rope **32**, and fourth rope **34** are removed from pouch **36**.

Free end **28a** of rope **28** is pulled around a support structure, such as a tree **46**, and is tied either to a selected location of rope **28** or to a free end of rope **34** which also has been pulled around tree **46**.

Free end of rope **22** is staked to the ground.

First loop **12** is staked to the ground.

Second loop **18** is staked to the ground.

The foregoing illustrates some of the possibilities for practicing the invention. Many other embodiments are possible within the scope and spirit of the invention. It is, therefore, intended that the foregoing description be regarded as illustrative rather than limiting, and that the scope of the invention is given by the appended claims together with their full range of equivalents.

What is claimed is:

1. An outdoor shelter comprising:
a planar single tarp having a planar body;
a first loop at a first corner of the planar body on a first edge of the tarp, the first loop secured to a ground surface using a first elongated member;

a second loop at a second corner of the planar body on the first edge of the tarp, the second loop secured to the ground surface using a second elongated member;

a first rope and a third rope at a first corner of the tarp on a second edge of the planar body opposite and parallel to the first edge of the planar body, the first rope and the third rope are secured to a structure extending vertically from the ground surface;

a second rope and a fourth rope at a second corner of the tarp on the second edge of the tarp, the second rope and the fourth rope are secured to another structure extending vertically from the ground surface; and

a pouch having three sides fixed to the planar body and sized to contain the tarp, the first loop, the second loop, the first rope, the second rope, the third rope and the fourth rope.

2. The outdoor shelter according to claim 1, wherein the tarp has the shape of a lean-to when deployed.

3. The outdoor shelter according to claim 1, wherein the pouch is fixed to the tarp at a corner of the tarp.

4. The outdoor shelter according to claim 1, wherein the tarp is made of a waterproof, flexible, tear-resistant material.

5. The outdoor shelter according to claim 4 wherein the tarp is made of Xenon.

6. The outdoor shelter according to claim 4, wherein the tarp has the shape of a lean-to when deployed.

7. The outdoor shelter according to claim 6, wherein the pouch is fixed to the tarp at a corner of the tarp.
